UNITED STATES PATENT OFFICE.

CHARLES B. HALSTEAD AND HENRY H. HALSTEAD, OF RANTOUL, ILLINOIS.

ROTARY STEAM-ENGINE.

SPECIFICATION forming part of Letters Patent No. 249,345, dated November 8, 1881.

Application filed June 6, 1881. (Model.)

To all whom it may concern:

Be it known that we, CHARLES B. HALSTEAD and HENRY H. HALSTEAD, citizens of the United States, residing at Rantoul, in the county of Champaign and State of Illinois, have invented certain new and useful Improvements in Rotary Steam-Engines; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to rotary steam-engines; and it consists in certain improvements in the construction of the same and a novel arrangement of parts, as hereinafter fully shown and described.

In the accompanying drawings, Figure 1 represents an interior view of the device, showing the piston-wheel in its chamber. Fig. 2 also shows an interior view, the piston-wheel being removed. Fig. 3 represents a vertical transverse section.

A designates the casing, which is shown as made in two parts bolted together, said parts being recessed to form a chamber for the piston-wheel B on the shaft a, which has suitable bearings, as shown. The piston-wheel has a number of radial pistons, D, four being preferred and shown, each piston being made flat and flaring outward, and ending inward with a small shaft, c, passing into a socket in the hub C, so that the piston is free to turn, as herein-after stated. The piston-chamber is divided by the projections b, extending toward each other from both sides of the chamber, said projections being provided with suitable packing, and leaving enough space between them for the piston to pass through edgewise. The turning of each piston D is effected by means of cogs or teeth d on its shaft c, the hub C being recessed for them, as shown. These cogs, coming in contact with an irregular or recessed surface, E, adjacent to the hub, cause the piston to turn, one impingement turning it edgewise, as shown in Fig. 1, so that it stands across the chamber, fitting the space, the edges of the piston having suitable packing.

F and F' are the upper pipes, severally leading to each division of the piston-chamber, and G and G' are the lower pipes, communicating

with each division in like manner. These pipes 55 serve for the admission and discharge of steam, as when steam is admitted through pipes F and G the wheel is rotated in one direction, and the other two pipes are discharge-pipes; and when, to reverse the engine, steam is admitted through F' and G', the wheel is rotated 60 in the opposite direction, and the pipes F and G become discharge-pipes.

Supposing the piston-wheel to be in the position shown in Fig. 1, two of the pistons being in the same plane with the wheel and two standing across the chamber and on a horizontal line, and steam is admitted through pipes F and G, one of the ends of the section of the wheel B and the projections b b form the 70 abutment against which the steam reacts. The steam passing from said pipes in the direction indicated by the arrows x is caught by the two horizontal pistons, and the wheel B is rotated in the direction indicated by the arrows, the 75 pipes F' and G' being discharge-pipes. So, as will be observed, each piston D takes alternately two positions in the chamber or cylinder as the wheel B is rotated. In one position the piston stands in the same plane with the 80 wheel, so that it may pass between the projections b, and after such passage it is turned to a position edgewise and across the chamber by a cog, d, impinging against the irregular surface E, the parts being usually so constructed 85 and arranged that the piston changes its position once in each quarter of a revolution of the wheel B.

Having described our invention, we claim—

1. In a rotary steam-engine, a piston-wheel 90 having pistons D, provided with cogs d, in combination with an irregular surface, E, substantially as and for the purposes described.

2. In a rotary engine, the piston-wheel chamber having the central inward projections, b, 95 and the pipes F F' and G G', communicating with the chamber, as shown, in combination with wheel B, having pistons D, provided with cogs d, and the irregular surface E, substantially as and for the purposes described. 100

In testimony whereof we affix our signatures in presence of two witnesses.

CHARLES B. HALSTEAD.
HENRY H. HALSTEAD.
